UNITED STATES PATENT OFFICE

2,679,376

MULTIPLE PORT VALVE

Frank J. Steiner, Rockford, Ill., assignor to Automatic Pump & Softener Corporation, Rockford, Ill., a corporation of Illinois

Application April 28, 1952, Serial No. 284,791

7 Claims. (Cl. 251—58)

1

This invention relates to valves and has special reference to multiple port rotary type valves.

An important object of the invention is the provision of a valve of the character described wherein the fluid pressures acting on opposite sides of the rotary member are brought substantially into balance prior to rotation.

Another object is to provide a lift turn type valve wherein communication to atmosphere is closed prior to lifting the rotor.

A still further object of the invention is the provision of a multiple port valve of the type having a port communicating with a drain or other point at atmospheric pressure wherein said port is closed and fluid pressure is admitted thereto prior to turning the rotor to substantially balance the pressure on opposite sides thereof prior to rotation.

Another object is the provision, in a valve of the class described, of novel auxiliary valve structure for closing the communication through one of the ports in the body and for establishing communication between the port and a source of fluid pressure in the valve.

Other objects and advantages will appear from the following description and the accompanying drawings, in which—

Figure 1 is a longitudinal section through a valve embodying the invention taken along the line 1—1 of Fig. 4 showing the valve in the normal service position;

Fig. 2 is a sectional view showing the cam arrangement, the cams being shown in elevation;

Fig. 3 is a view on the line 3—3 of Figure 1 showing the top of the stem plate or rotor;

Fig. 4 is a view on the line 4—4 of Figure 1 showing the face of the body and gasket;

Fig. 5 is a fragmentary section through the body and rotor taken along the line 5—5 of Fig. 4, showing the rotor in its first moved position, and

Figs. 6 and 7 are fragmentary views similar to Figure 1 showing steps in the movement of the rotor.

The invention is shown embodied in a multiport valve of the lift turn type which have in the past largely been used to control the liquid flows in base exchange water softeners and filters. The present embodiment includes a body member indicated generally by the numeral 8 having an annular top flange 9, it being understood that terms such as "top" and "bottom" as used herein are intended to be relative and refer only to the positions as shown in the drawings. A rotor housing 11, likewise having an annular bottom flange 12 is secured to the top of the body by means of spaced bolts 13 passing through the flanges and through a sealing gasket interposed between the flanges. The rotor housing 11 also has a top flange 14 to which a cover 15 is attached

2

by means of a cover flange 16, the annular outer edge 17 of a diaphragm 18 being interposed between the flanges 14 and 16 and secured in fluid tight relation thereto by annularly spaced bolts 19. The cover 15 carries a centrally disposed cam mechanism indicated generally by the numeral 21 which will presently be described in more detail.

Referring now to the structural details of the body 8 shown in Figures 1 and 4, the body has a flat top face member 22, in this instance of circular configuration inasmuch as the illustrated embodiment of the valve is of generally circular cross-sectional shape. As will be seen from Figure 1, the flange 9 is a continuation of the face member. The body also includes concentric tubular body walls 23 and 24 extending downwardly from the face member, the outer walls 23 converging inwardly in spaced relation to the face member, as shown at 25, and merging with the wall 24. The lower end of the tubular wall 24 carries a conventional pipe flange 26 or other means for connection thereto. Pipe connections 27 and 28 are provided through the wall 23 in the form of nipples, integral with the wall 23, carrying conventional pipe flanges 29 and 31. The space between the walls 23 and 24 is divided into two separate chambers 32 and 33 by longitudinally disposed imperforate walls 34 and 35, the pipe connections 27 and 28 each communicating with one of the chambers.

The face member 22 is provided, in this embodiment, with six annularly spaced openings communicating with the chambers 32 and 33 forming ports for the selective passage of fluid therethrough, ports 36, 37 and 38 opening into chamber 32 and ports 39, 41 and 42 opening into chamber 33. The face member 22 also has a port opening 43 communicating with a tube 44 sealed at one end to the face member, extending through the chamber 33, out through the bottom of the body and sealed to the bottom as shown at 45. A central port 46 in the face member communicates with a chamber 47 defined by the walls 24. Disposed upon the upper side of the face member 22 is a gasket 48 of rubber or other suitable resilient gasket material, in this instance connected to the face member 22 and provided with openings therethrough corresponding in shape and size with the ports 36 through 39 and 41, 42, 43 and 46.

Each of the ports 38 and 42 are provided with a flow restricting or throttling valve of identical construction, each comprising a thimble 49 threaded into the port in the face member and depending into the chamber beneath. The thimble is open at its lower end and in the embodiment shown has four slots as indicated at 51 extending upwardly from its bottom edge. A plunger 52 fits within the thimble and is mounted on a stem 53 projecting downwardly through the

chamber and through a boss 54. The lower end of the stem is threaded and passes through the threaded bore of a cap 55 secured against the bars 54 by screws 56, the stem carrying a jam nut 57 for locking the stem in adjusted position. A slot 58 at the end of the stem is adapted to receive a tool for rotating the stem to adjust the position of the plunger 52 in the thimble and thereby determine the area of slots 51 through which flow may occur between the bottom chamber and the ports 38 or 42.

The rotor housing 11 has an inlet pipe connection 59 provided with the usual pipe flange 61 for connection into a system of piping in the usual manner. Disposed within the housing is a rotor 62 having a substantially flat lower face adapted to seat on the gasket 48 and to control the fluid flow through the ports in the face member. As best shown in Fig. 3, the rotor has an open port 63 extending therethrough on substantially the same radius as the ports in the face member to permit communication between the chamber 64 within the housing 11 and certain of the ports in the face member in the various positions of the rotor and has a transfer passage 65 registering at all times with the central port 46 and selectively registerable with certain annular ports of the face member to establish communication therebetween in the various positions of the rotor. The bottom surface of the rotor is otherwise imperforate. According to the present invention there is centrally disposed on the rotor a supporting flange 66 for connecting the rotor to a centrally disposed stem 67, a sleeve 68 of an auxiliary valve disk 69 being interposed between the flange and the stem. The rotor is attached to the stem by a pin 71 threaded into the rotor and passing through a slot 72 in the stem to provide lost motion therebetween, the pin also passing through slots 73 in the sleeve 68 to provide lost motion between these ports. The valve disk 69 overlies a portion of the upper side of the rotor and has a gasket 74 cooperating therewith to control flow between the chamber 64 and the transfer passage 65 through a plurality of passages 75. An O ring seal 70 is disposed between the stem sleeve 68 adjacent the upper end of the latter to prevent leakage along the interface.

The stem carries a collar 76 attached thereto below the supporting flange 66 and passes through a guide 77 forming part of a spider having an annular mounting sleeve 78 affixed in the port 46. The stem extends into the chamber 47 and carries an auxiliary valve plate 79 of substantially smaller dimensions than the chamber adapted in the upward movement of the stem to engage against the bottom of a valve ring 81, snugly received in chamber 47 to close the central opening 82 in the ring and to raise the ring free of supporting lugs 83 attached to side walls 24 and projecting into the chamber 47, to support the ring in the lower position of the stem.

The diaphragm 18, which has its perimeter clamped in a fluidtight manner between flanges 14 and 16 forms with associated parts the upper wall of chamber 64 and the lower wall of a chamber 60, and has a central opening for the passage of stem 67. The stem is attached to the diaphragm by means of a pair of clamping plates 84, the inner edge of the diaphragm being clamped between the plates by action of bolts 85 which draw the outer edges of the plates together to compress the diaphragm therebetween in fluidtight fashion. A spacer plate 86 is disposed between the clamping plates for obvious reasons.

The stem carries an externally threaded sleeve 87 within which the stem is capable of rotation, the clamping plates and spacer having a central opening for the reception of the sleeve so that the clamping assembly seats against a shoulder 88 on the sleeve and is held thereagainst by a nut 89 threaded onto the sleeve and bearing against the upper side of the clamping assembly. The nut is held against rotation by a lock screw 91 engaging the clamping assembly. A split ring 92 is disposed in adjoining recesses in the stem and sleeve and bears the end thrust occasioned by lifting of the stem and rotor by action of the diaphragm, and a lip 93 on the nut serves to prevent more than very limited movement of the sleeve axially downward with respect to the stem.

The cam mechanism 21 is centrally mounted on the cover 15 which has an integral mounting flange 94 to which a cam housing 95 is bolted, a gasket being interposed therebetween. Surrounding the stem is a lower cam member (best shown in Fig. 2) having an annular flange portion 96 secured against the mounting flange 94 by cap screws 97 with a gasket interposed therebetween for sealing purposes and a cam portion 98 disposed within the cam housing 95. The cam member carries an O ring seal 99 to seal the interface along the shaft. An upper cam member has a flange portion 101 secured across the upper end of the cam housing and a depending cam portion 102 disposed in spaced relation to the lower cam portion 98 for the reception therebetween of followers in the form of projecting ends of a pin 103 secured in the stem. The stem projects above the flange portion 101 in the seated position of the valve and the projecting end is enclosed by a cap 104 secured to the flange portion and extending upwardly a distance sufficient to permit rising of the stem. Communicating with the chamber 60 defined by the diaphragm and the cover 15 is an inlet connection 105 of relatively small size and an outlet connection 106 of substantially larger size than the inlet connection having a valve 107 for controlling the outlet flow from the chamber 60.

Operation

Since valves of this character are principally used as part of base exchange liquid treatment apparatus and filters for the purpose of controlling liquid flows in such a system, its operation will be described in that environment.

The connection 59 is connected to a source of liquid to be treated which enters the valve under pressure. The valve connection 27 may be connected to the top of the treatment tank, the connection 28 to the bottom of the tank, and the connection 26 to a main or point of waste disposal. When the rotor is seated in the normal or service position as shown in Figure 1, fluid under pressure (which may in many instances be the liquid being supplied through connection 59) is supplied to the chamber 60 through connection 105, and the diaphragm and rotor are retained in the position shown. When the rotor occupies the normal or so-called service position, the rotor port 63 registers with body port 37, permitting fluid to flow from connection 59, through chamber 64, ports 63 and 37, chamber 32 and connection 27 to the top of the treatment tank.

To shift the rotor to its next position the control valve 107 is opened to establish communication between the chamber 60 and a point of

low pressure, preferably atmospheric or even lower and allow the fluid to drain from the chamber and the pressure therein to fall to a point substantially below that in chamber 64. The difference in pressure between the two chambers causes the diaphragm to move upwardly until the nut 89 engages the flange portion 96, bringing the stem 67 upwardly to the same extent by action of sleeve 87 on ring 92.

During the initial part of the upward movement of the stem the slot 72 permits the stem to move with respect to the pin 71 so that the valve plate 79 engages the valve ring 81, closing the central opening 82, and terminating communication between drain port 46 and the drain connection. Upon further upward movement of the stem, the plate 79 raises the ring 81 from lugs 83 as shown in Figs. 6 and 7 to maintain the drain line closed. With continued upward movement of the stem the collar 76 engages the lower end of the sleeve 68 causing the sleeve and valve disk 69 to move upwardly in the supporting flange 66, the slots 73 permitting such relative movement. This moves the disk upwardly away from the rotor and opens communication between the passage 65 and the chamber 64 through openings 75 as shown in Fig. 6, allowing the hydraulic pressure within the passage and drain port to become substantially equal to that in the chamber 64. When the stem brings the collar 76 against the lower end of supporting flange 66, continued upward movement of the stem raises the lower face of the rotor free or substantially free of the gasket 48, the position of the ports at this point being shown in Fig. 7.

Referring now to Fig. 2, during the upward movement of the stem just described the ends of the pin 103 move vertically upward between parallel faces 108 at diametrically opposite sides of the lower cam. At the point in the upward movement of the stem at which the rotor is substantially free of the gasket the ends of the pin come into engagement with helically disposed faces 109 of the upper cam and with continued upward movement of the stem slide along these faces to rotate the stem and, through the pin 71, rotate the rotor through 45 degrees when the cam pin enters between parallel faces 111 of the upper cam.

When the control valve 107 is closed, fluid entering chamber 60 through connection 105 causes the pressure to build up to a point equal or exceeding that in chamber 64, whereupon the diaphragm and stem move down. During downward movement the ends of the cam pin first move down between parallel faces 111 of the upper cam until the contact helical faces 112 of the lower cam and they then slide along this face, rotating 45 degrees, until they reach the succeeding pairs of parallel faces 108 of the lower cam. At this point in the downward or reseating movement of the stem, the rotor has been turned through 90 degrees and the lower face of the rotor is returned approximately to contact with the gasket 48. As the stem continues its downward movement the rotor contacts the gasket and the collar 76 moves away from the end of support flange 66 allowing valve disk 69 to reseat on the top of the rotor. Subsequently the valve ring 81 engages the lugs 83 and the valve plate 79 moves away from the ring to reopen the drain, and bring the valve ports to the next seated position, with the open rotor port 63 in registration with body port 39 and the transfer

passage in registration with body port 38 bringing the parts to the position shown in Fig. 5.

In this position of the valve liquid flows from chamber 64 through ports 63 and 39, chamber 5 33 and connection 28 to the bottom of the treatment tank and from the top of the treatment tank through connection 27, chamber 32, port 38, transfer passage 65 and port 46 to drain, the rate of flow being determined by the adjusted position of the restriction at port 38.

By repeatedly opening and closing control valve 107 the rotor is moved by 90 degree steps through a complete cycle of 360 degrees back to the service position. Thus, in the third position 15 of the rotor, the rotor port 63 registers with body port 43 to supply liquid to an external eductor and transfer passage 65 register with body port 41 to permit flow from the bottom of the treatment tank to drain, and in the fourth position 20 of the rotor the open rotor port 63 registers with body port 36 to supply rinse liquid to the top of the tank and transfer passage 65 registers with body port 42 to connect the bottom of the tank to drain, the flow in this position also being determined by the adjustment of the restriction at 25 port 41.

I claim:

1. A plate type valve comprising in combination a body member having a plurality of ports, 30 one of said ports being a low pressure port, a ported rotor cooperable with the body member adapted to effect different communication between the body ports in different positions of the rotor, a rotor housing member on the body forming a chamber enclosing the rotor, one of said members having a supply port communicating with the interior of the housing member to supply fluid to the valve and apply seating pressure against the rotor, an auxiliary valve in the body 35 for controlling flow through the low pressure port, an auxiliary valve on the rotor for controlling communication between the low pressure port and the housing chamber, a stem associated with the rotor having longitudinal movement with respect thereto and rotatable to turn the rotor between different operative positions, and means acting between the stem and said auxiliary valves to close the auxiliary low pressure port valve and open the auxiliary rotor valve in response to movement of the stem longitudinally 40 in one direction to admit pressure to the low pressure port prior to turning the rotor, and to close the auxiliary rotor valve and open the auxiliary low pressure port valve upon longitudinal return movement of the stem in the opposite direction.

2. A multiport valve comprising in combination a body member having a plurality of ports, 45 one of said ports being a low pressure port, a rotor cooperable with the body member having a plurality of ports adapted for different registration with the body ports in different positions of the rotor, a rotor housing member attached to the body forming a chamber enclosing the rotor, one of said members having a supply port normally communicating with the interior of the housing member to supply fluid under pressure to the valve and apply seating pressure against the rotor, an auxiliary valve for controlling flow through the low pressure port, an auxiliary valve on the rotor for controlling communication between the low pressure port and the housing chamber, a stem associated with the rotor having longitudinal movement with respect thereto and rotatable to turn the rotor

between different operative positions, and means connecting the stem to said auxiliary valves to first close the auxiliary low pressure port valve and then open the auxiliary rotor valve in response to movement of the stem longitudinally in one direction and to first close the auxiliary rotor valve and thereafter open the auxiliary low pressure port valve upon longitudinal return movement of the stem in the opposite direction.

3. The combination in a multiple port valve of a body member having a ported face provided with a plurality of ports, one of said ports being a centrally disposed low pressure port, a ported rotor cooperable with the body member having a plurality of ports adapted for different registration with the body ports in different positions of the rotor, said rotor ports including a passage interconnecting the low pressure port and certain of the other body ports in various positions of the rotor, a rotor housing member on the body forming a chamber enclosing the rotor, one of said members having a supply port normally communicating with the chamber to supply fluid under pressure thereto for passage through the valve and placing the chamber under pressure, an auxiliary valve for controlling flow through the low pressure port, an auxiliary valve on the rotor for controlling communication between the rotor passage and the chamber, a stem associated with the rotor having longitudinal movement with respect thereto and rotatable to turn the rotor between different operative positions, and means connecting the stem to said auxiliary valves to close the auxiliary low pressure port valve and open the auxiliary rotor valve in response to movement of the stem longitudinally in one direction to bring the fluid pressure within the rotor passage substantially to that of the chamber, and to close the auxiliary rotor valve and open the auxiliary low pressure port valve upon movement of the stem in the opposite direction to reestablish low pressure conditions within the passage.

4. The combination recited in claim 1 wherein the low pressure port valve includes a tubular passage communicating with the low pressure port, a ring slidable in said tube and having a central opening for the passage of fluid to the low pressure port, means for supporting the ring in the tube, and a valve disk attached to the stem positioned to engage the ring and cover the central opening and thereafter slide the ring in the tube upon movement of the stem in said one direction and to return the ring to its support and uncover the central opening upon return movement of the stem in said opposite direction.

5. A plate type valve comprising in combination a body member having a plurality of ports, one of said ports being a low pressure port, a ported rotor cooperable to effect different communication between the ports in different positions of the rotor, the rotor having a passage in communication with the low pressure port, a rotor housing member on the body forming a chamber enclosing the rotor, one of said members having a connection communicating with the chamber to supply fluid under pressure for passage through the valve and placing the chamber under pressure, a stem passing through the rotor and into the low pressure port having a lost motion connection to the rotor for longitudinal movement with respect thereto, an auxiliary low pressure port valve in the body operated by longitudinal movement of the stem in one di-

rection to close the valve and by return movement to open the valve, an auxiliary rotor valve member on the stem normally closing an opening through the rotor between said chamber and said passage, said rotor valve member having a lost motion connection with said stem, means for opening the rotor valve member subsequent to the closing of the low pressure port valve in response to movement of the stem in said one direction to raise the pressure in said passage and for closing the rotor valve member prior to opening of the low pressure port valve upon return movement of the stem, and means acting between the stem and the rotor for turning the rotor.

6. A multiport valve comprising in combination a body member having a plurality of ports, one of said ports being a low pressure port, a ported rotor cooperable with the body member adapted to effect different communication between the body ports in different positions of the rotor, a rotor housing member on the body forming a chamber enclosing the rotor, one of said members having a supply port communicating with the interior of the housing member to supply fluid to the valve and apply seating pressure against the rotor, an auxiliary valve in the body for controlling flow through the low pressure port, an auxiliary valve on the rotor for controlling communication between the low pressure port and the housing chamber, means for turning the rotor between different operative positions and means operative to first close the auxiliary low pressure port valve and then open the auxiliary rotor valve prior to turning of the rotor and operative to first close the auxiliary rotor valve and thereafter open the auxiliary low pressure port valve after turning of the rotor.

7. A multiport valve comprising in combination a body member having a plurality of ports, one of said ports being a low pressure port, a ported rotor cooperable with the body member adapted to effect different communication between the body ports in different positions of the rotor, a rotor housing member on the body forming a chamber enclosing the rotor, one of said members having a supply port communicating with the interior of the housing member to supply fluid to the valve and apply seating pressure against the rotor, an auxiliary valve in the body for controlling flow through the low pressure port, an auxiliary valve on the rotor for controlling communication between the low pressure port and the housing chamber, rotor turning means associated with the rotor having a lost motion connection thereto and rotatable to turn the rotor between different operative positions, and connections from said rotor turning means to said auxiliary valves to first close the auxiliary low pressure port valve and then open the auxiliary rotor valve prior to turning of the rotor and to first close the auxiliary rotor valve and thereafter open the auxiliary low pressure port valve after turning of the rotor.
